UNITED STATES PATENT OFFICE.

HERBERT B. NEWTON, OF BROOKLINE, MASSACHUSETTS.

HOSE-LEG SUPPORTER.

1,424,771.

Specification of Letters Patent. Patented Aug. 8, 1922.

Application filed August 12, 1921. Serial No. 491,675.

To all whom it may concern:

Be it known that I, HERBERT B. NEWTON, a citizen of the United States, residing at Brookline, in the county of Norfolk and State of Massachusetts, have invented new and useful Improvements in Hose-Leg Supporters, of which the following is a specification.

This invention relates to a hose leg 10 porter, adapted to be worn within a hose leg and to be supported in its operative position by the ankle protuberances of the wearer, without binding contact with any part of the wearer's leg.

15 The invention is embodied in the improvements which I will now proceed to describe and claim.

Of the accompanying drawings forming a part of this specification,—

20 Figure 1 is a side view of a hose leg supporter embodying the invention, shown mainly by dotted lines within a hose leg.

Figure 2 is a perspective view of the supporter.

25 Figure 3 is a fragmentary section on line 3—3 of Figure 1, showing one form of hose leg-engaging means.

Figure 4 is an enlarged perspective view of the strap-engaging portion of the wire 30 standard.

Figure 5 is a view similar to Figure 4, showing a portion of the strap.

Figure 6 is a perspective view of the upper end portion of the standard, showing a 35 different form of hose leg-engaging means.

The same reference characters indicate the same parts in all of the figures.

My improved supporter comprises a band 40 adapted to embrace the leg immediately above the ankle, protuberances, one of which is shown at 12 in Figure 1, and a standard 14 supported by, and projecting above the band, and adapted to engage the upper end portion of a hose leg 16.

45 The band is preferably formed by detachably connecting or coupling together the end portions of a strap 17, of inelastic webbing, or other suitable material. The standard is preferably made of wire, which may 50 be non-corrosive, or plated or coated to render it non-corrosive and inoxidizable. One end of the standard is provided with suitable means for engaging the strap 17, preferably in such manner as to permit a variation of its operative length and of the diameter of the band into which it is converted,

and with a coupling member inseparably attached to the strap-engaging means, and adapted to detachably engage a complementary coupling member on the free end of the 60 strap. The opposite end of the standard is provided with suitable means for engaging the upper end portion of the hose leg.

I prefer to provide the strap-engaging means and the coupling member attached thereto by bending one end portion of the wire to the form shown enlarged by Figure 4. One extremity of the wire forms an eye 20, embracing a neck 21 which connects the main body of the standard with a bar portion 22, extending parallel therewith. A neck 23 connects the bar portion 22 with an arm portion 24, which is connected by a looped portion 25 with another arm portion 26, on which the eye 20 is formed. The looped portion 25 constitutes a coupling member or eye, with which cooperates a complementary coupling member or hook 27, directly attached to the free end of the strap 17. The opposite end portion of the strap is passed between the bar portion 22 and the arm portions 24 and 26, and around the body portion of the standard 14, the extremity of the strap being interposed between the bar portion 22 and the main portion of the strap, as indicated by Figure 5. Provision is thus made for adjusting the strap longitudinally to vary its operative length and the diameter of the band formed by the strap when the coupling members are connected. Any other 80 suitable means may be provided for engaging the standard with the strap, and for providing the standard with a coupling member.

The upper end of the standard may be 95 provided with a loop 29, the sides of which converge toward each other from the outer end of the loop. A fold 16^a of the hose leg may be inserted in the loop 29, and a disk 30, such as an ordinary garment button, may 100 be passed edgewise through the loop and into the fold, and then turned so that when a downward pull is exerted on the hose leg, portions of the fold will be gripped between the disk 30 and the sides of the loop, as 105 shown by Figure 3, the disk being of greater diameter than the lower portion of the loop. This is one of many forms of means which may be employed for engaging the upper end of the standard with the hose leg.

One alternative form of means for the same purpose is shown by Figure 6, in which

the loop is coiled at 31, the convolutions being adapted to be sprung apart and receive a portion of the hose leg between them.

It will be seen that the strap 17 may be converted into a band of suitable diameter to loosely embrace the wearer's leg immediately above the ankle. The band, although so loose that it cannot bind the leg, is prevented by the ankle protuberances below it from slipping downward, hence it supports the standard, the latter in turn supporting the hose leg.

The standard may be of any other suitable material and construction.

15 The strap-engaging means and the coupling member, inseparably attached thereto, prevent accidental displacement of the standard lengthwise of the band formed by the strap. In other words, the standard is 20 prevented from slipping on the band toward or from the coupling.

I claim:

1. A hose leg supporter comprising a standard formed to extend beside a portion 25 of a human leg above the ankle, and provided at one end with hose leg-engaging means, and at its opposite end with strap-engaging means and with a coupling member inseparably attached to said means, and a

strap adjustably connected at one end portion with the engaging means, and having a free end provided with a complementary coupling member, the interengagement of said coupling members converting the strap into a band adapted to loosely embrace the wearer's leg immediately above the ankle, the said strap-engaging means, and the coupling attached thereto, preventing displacement of the standard lengthwise of the band. 30

2. A hose leg supporter comprising a length of wire, bent at one end portion to form strap-engaging means and a coupling member, and at its opposite end portion to form hose leg-engaging means; and a non-elastic strap adjustably connected at one end 45 portion with said strap-engaging means; so that its operative length may be varied and provided at its opposite end with a complementary coupling member, the band formed by the interengagement of said coupling members being adapted to loosely embrace the wearer's leg immediately above the ankle, and to be supported against downward movement by the ankle protuberances, without exerting binding pressure on the leg. 50

In testimony whereof I have affixed my signature.

HERBERT B. NEWTON.
